UNITED STATES PATENT OFFICE.

MANUEL SILVA PEREIRA AND CUSTODIO SILVA, OF BROOKLYN, NEW YORK.

BEARING.

1,278,500.

Specification of Letters Patent. Patented Sept. 10, 1918.

Application filed March 7, 1918. Serial No. 220,982.

To all whom it may concern:

Be it known that we, MANUEL SILVA PEREIRA and CUSTODIO SILVA, subjects of the King of Spain, and residents of the borough of Brooklyn, in the city and State of New York, have invented a new and useful Improvement in Bearings, of which the following is a specification.

This invention relates to an improvement 10 in bearings for rods, shafts and the like, and more particularly to hinged bearings, with the object in view of providing a device which may be readily released or locked for the purpose of quickly removing or re-15 placing a rod or shaft.

A further object is to provide a device which may be arranged in series and operated by a common means, which releases or locks the parts simultaneously.

20 A still further object is to provide certain improvements in the form, construction and arrangement of the elements whereby the above and other named objects may be effectively carried out.

25 A practical embodiment of our invention is represented in the accompanying drawings in which,

Figure 1 represents in front elevation two 30 of our improved bearings having the locking and releasing means connected and operated by a means common to both bearings.

Fig. 2 represents a side elevation of the same partly in section.

Fig. 3 represents a longitudinal vertical 35 section taken in the plane of the line III-III of Fig. 1.

Fig. 4 represents a front elevation of a modified form of bearing.

Fig. 5 represents a vertical central section 40 of the same.

Fig. 6 represents a front elevation of a hanger used in connection with shafting, and having our improved construction applied thereto.

Fig. 7 represents a side elevation of the same, and

Fig. 8 represents a vertical central section.

The upper and lower bearings shown in Figs. 1, 2 and 3, are more or less similar in 50 construction and are the same in so far as the operation of the movable parts are concerned.

Each bearing comprises a fixed member 1 and a movable member 2. The fixed member 1 has a portion 3 arranged to receive 55 a rod or shaft 4 and the movable member 2

a corresponding portion 5 which coacts with the portion 3 to hold the rod therebetween when in a closed position. The movable member 2 is hinged to the member 1 at 6, 60 so that the portion 5 of the movable member may be swung to the position shown in dotted lines in Fig. 3, thereby leaving the rod free to be removed.

The movable member 2 is held in engagement with its fixed member 1 by means of hooks 7, in the present instance two are shown, secured to a yoke 8 which is fast on a longitudinally movable bar 9 journaled in a frame 10 of the member 1. This frame 70 10 also serves as a guide for the movement of the yoke 8. The hooks 7 project downwardly into a pocket 11 in the member 1 and outwardly into elongated slots 12 in the movable member 2.

The movement of the bar 9 in the frame 10 is controlled by means of a nut 13 having a screw-threaded engagement with the upper end of the bar and resting upon the frame 10. Thus it will be seen that when 80 the bar 9 is moved upwardly, the yoke 8 will carry the hooks 7 upwardly in the pocket 11 and slots 12, until they engage the member 2 at the top of the slots, whereupon the rod 4 will be securely locked between the members. The downward movement of the bar 9 will, of course, cause the hooks to pass downwardly in the slots until they have released the member 2 which will fall by gravity to the position shown in 90 Fig. 3.

As a means of securing the device to a wall 14 or other support, we provide the member 1 with flanges 15 arranged to receive bolts 16 screwed into the wall.

In order to operate a series of bearings simultaneously, it is necessary to form the upper fixed member with a bridge 17 so that the bar 9 may pass through the same to the yoke of the bearing below.

To accommodate rods having spurs, pins or other projection thereon, the movable member 2 is bifurcated as shown at 18 in Fig. 1, so that the spur 19 may oscillate therein.

In the form shown in Figs. 4 and 5, the fixed member 20 is provided with a pocket 21 in which a hook 22 reciprocates, the shank of which hook is arranged to move vertically in a hole 23 in the member 20 at the top of the pocket and has a screw-threaded engagement with a nut 24 which controls the move-

ment of the hook. The movable member 25 is provided with a slot 26 in which the hook 22 reciprocates and is locked and released similar to the manner previously described.

5. In Figs. 6, 7, and 8, we have shown a hanger for shafting in which the members do not directly engage the shaft but support shaft bearings such as are now in common use. The fixed member 27 of the hanger is 10 provided with straps 28 by which it is secured to the overhead timbers 29. The movable member 30 is hinged at 31 so that it may swing to a position as shown in dotted lines in Fig. 8 and held in snug engagement 15 with the fixed member 27 by a hook 32 which is moved vertically in slots 33, 34, in the members by means of a nut 35 having a screw-threaded engagement with the shank of the hook 32 and bearing upon the fixed member 27 between the straps 28.

The device shown in Figs. 1 and 3 inclusive is well adapted for use in connection with the protectors for vessels shown in our co-pending application Serial No. 204649, filed November 30, 1917.

It is evident that various changes may be resorted to in the form, construction and arrangement of the several parts without departing from the spirit and scope of our invention and hence we do not intend to be limited to the details shown and described except as they may be specifically set forth in the claims.

What we claim is:

85. 1. A bearing for rods, shafts and the like comprising members hinged together, and a reciprocating means for locking and releasing said members.
2. Bearings for rods, shafts and the like comprising sets of members hinged together and a common means for locking and releasing said members.
3. Bearings for rods, shafts and the like comprising sets of members hinged together and a common reciprocating means for locking and releasing said members.
4. A bearing for rods, shafts and the like

comprising fixed and movable members hinged together and a reciprocating means for locking and releasing said members. 50

5. A bearing for rods, shafts and the like comprising fixed and movable members hinged together and means reciprocable in said fixed member and engaging said movable member for locking the members together. 55

6. A bearing for rods, shafts and the like comprising a fixed member, a movable member hinged thereto and having a slot therein, a hook arranged to enter said slot and means 60 for reciprocating said hook for locking and releasing said members.

7. A bearing for rods, shafts and the like comprising a fixed member, a movable member hinged thereto and a yoke, slidable in 65 said fixed member and having hooks arranged to engage said movable member for locking the members together.

8. A bearing for rods, shafts and the like comprising a fixed member, a movable member hinged thereto, a yoke, slidable in said fixed member and having hooks arranged to engage said movable member and means for reciprocating said yoke and hooks for locking and releasing the members. 70

9. Bearings for rods, shafts and the like comprising fixed members, movable members hinged thereto, a bar having hooks arranged to engage said movable members and means for reciprocating said bar for locking and 80 releasing said members.

10. Bearings for rods, shafts and the like comprising fixed members, movable members hinged thereto, a bar provided with yokes having hooks arranged to engage said 85 movable members and means for reciprocating said bar for locking and releasing said members.

In testimony, that we claim the foregoing as our invention, we have signed our names, 90 this fifth day of March, 1918.

MANUEL SILVA PEREIRA.
CUSTODIO SILVA.
